TOY MUSICAL INSTRUMENT

Raymond J. Lohr, Erie, Pa., assignor to Louis Marx & Company, Inc., New York, N.Y., a corporation of New York

Application October 8, 1959, Serial No. 57,857

Term of patent 7 years

(Cl. D34—15)

Fig. 1.

Fig. 2.

Fig. 3.

Fig. 4.

Fig. 5.

Fig. 1 is a plan view of a toy musical instrument, showing my new design;

Fig. 2 is a front elevational view of the same;

Fig. 3 is a rear elevational view of the same;

Fig. 4 is an end view looking toward the left end in Figs. 1 and 2; and

Fig. 5 is an end view looking toward the right end in Figs. 1 and 2.

I claim:

The ornamental design for a toy musical instrument, substantially as shown.
